(No Model.)

S. H. SHORT.

TROLLEY SUPPORT FOR ELECTRIC RAILWAYS.

No. 569,772.

Patented Oct. 20, 1896.

UNITED STATES PATENT OFFICE.

SIDNEY H. SHORT, OF CLEVELAND, OHIO.

TROLLEY-SUPPORT FOR ELECTRIC RAILWAYS.

SPECIFICATION forming part of Letters Patent No. 569,772, dated October 20, 1896.

Application filed June 8, 1896. Serial No. 594,690. (No model.)

To all whom it may concern:

Be it known that I, SIDNEY H. SHORT, a citizen of the United States, residing at Cleveland, in the county of Cuyahoga and State of Ohio, have invented a new and useful Improvement in Trolley-Supports for Electric Railways, of which the following is a specification.

This invention relates to trolley-supports for electric railways.

The object of the invention is to provide a thoroughly efficient and practical trolley-support of simple and economical construction.

The invention consists, substantially, in the construction, combination, location, and relative arrangement of parts, all as will be more fully hereinafter set forth, as shown in the accompanying drawings, and finally specifically pointed out in the appended claims.

Referring to the drawings and to the various views and reference-signs appearing thereon, Figure 1 is a view in side elevation of a trolley and its support embodying the principles of my invention. Fig. 2 is a similar view showing the trolley in the position occupied thereby when in practical use. Fig. 3 is a sectional plan view on the line 3 3, Fig. 1. Fig. 4 is an enlarged broken detail view, in sectional plan, illustrating the manner of attaching the springs to the sliding sleeve on the trolley-pole. Fig. 5 is a broken detail view, in side elevation, of the construction shown in Fig. 4.

The same part is designated by the same reference-sign wherever it occurs throughout the several views.

In the construction and operation of electrical railways wherein is employed an overhead conductor and wherein current is supplied from such conductor to the motor on the car through a contact device arranged to make contact with the conductor upon the under side thereof it has heretofore been the custom in commercial practice to mount the underrunning contact or trolley wheel upon an arm or plate, which in turn is pivotally mounted on horizontal and vertical axes or pivots arranged transversely with respect to each other, whereby said arm or pole may rock or swing in intersecting planes, that is, said arm or pole may swing in a vertical plane about said horizontal axis or pivot toward

or away from the conductor and also may rock or swing laterally about or upon said vertical axis or pivot to reverse the direction of lead of such arm or support or to compensate for variations in the position of the conductor.

The present invention is designed upon entirely different principles. Instead of mounting the trolley pole or arm upon axes or pivots I entirely dispense with all pivots or axes.

In the practical application of my invention I provide a bracket or casting A, of suitable shape, size, and material, which may be supported in any suitable or convenient position upon the car, say, for instance, upon the roof of the car in case of use in connection with an overhead conductor. In the particular form shown, to which, however, I do not desire to be limited or restricted, the bracket or casting A is of square outline. At each of the four corners of the bracket or casting, in case the bracket or casting is of square or rectangular shape, or at four points spaced at suitable distances apart, I provide the posts B, to each of which is secured one end of each of a pair of springs.

Reference-sign C designates the trolley support or pole and may be of the usual or any desired or convenient size, shape, or material, and upon the upper or free end of which is mounted the trolley-wheel D or other contact device adapted to make contact with the conductor E. To the extreme lower end of the trolley pole or support C or adjacent to such end I secure the other end of one member 6 7 8 9 of each pair of springs, as most clearly shown in Fig. 3. A convenient method of attachment of the ends of springs 6 7 8 9 to the lower end of the trolley pole or support C is shown wherein I provide a small cylindrical sleeve 10, having a flange with eyelets corresponding in number and arrangement to the springs 6 7 8 9, and the ends of said springs are suitably secured in said eyelets. The sleeve 10 may be rigidly secured or mounted on the end of the trolley-pole in any suitable or convenient manner. A similar sleeve 11, having eyelets similar in number and arrangement to the eyelets in sleeve 10, is mounted loosely to slide freely upon trolley pole or arm C, and to the eyelets in

said sleeve are suitably secured the ends of other member 12 13 14 15 of the pair of springs above referred to.

In order to reduce friction, I may, if desired, 5 mount small rollers 16 in the sleeve 11 to form the bearing of such sleeve against the arm or pole C.

Upon the trolley arm or pole C and interposed between sleeves 10 11 I mount a spring 10 17, which tends to normally operate said sleeves. The combined action of the several 15 springs is to normally maintain the pole C in a vertical position, as indicated in Fig. 1, but a deflection of said pole in any direction is 20 permitted, which deflection will be against the action of the springs. When the pole is 25 in a vertical position, as shown in Fig. 1, the entire weight of the pole and trolley-wheel is supported upon the springs 6 7 8 9, said 30 springs being deflected or inclined downwardly from the posts B under the influence of such weight.

When the pole is deflected or bent over 35 into angular position to be placed upon the conductor, for instance, as shown in Fig. 2, such movement or deflection of the pole will 40 impart a tension to the upper springs 12 and 15 on one side and also to the lower springs 7 and 8 on the other side, while the upper 45 springs 3 and 4 and lower springs 6 9 will be correspondingly relaxed. The tension of 50 springs 12 15 being exerted in the opposite direction to that of springs 7 and 8 the tendency is to cause sleeve or collar 11 to slide 55 upon the trolley-pole C and toward sleeve 10, thereby effecting a compression of spring 17. The combined action of all these springs is 60 to tend to return the pole C to a vertically-upright position thereby securing a sufficient 65 upward pressure upon the trolley-wheel or contact end of the arm to pole to insure a good electrical contact with the conductor. The same action occurs in case the pole or arm C is deflected or bent in any other direction.

It will be observed the greater the deflection 70 of pole C from a vertical position the greater will be the tension imparted to the upper springs 12 15 and the lower springs 7 8 75 in the illustration above given, and as the tension on these springs increases the nearer will the sliding collar or sleeve 11 approach the fixed collar or sleeve 10, and hence the more spring 17 will be compressed. This 80 varying of the distance between collars or sleeves 10 11 results in a corresponding variation 85 in the fulcrum through which the springs act upon the pole C, and therefore by properly adjusting the spring 17 to the strength 90 of the other springs a uniform pressure can be maintained throughout the entire range of the deflection of the pole from a vertical to a horizontal position. This is a most important feature, and herein lies a most important 95 difference over trolley-poles which are mounted to vibrate on axes or pivots against the action of springs. In such cases, as is

evident, the greater the distance through which the trolley-pole is vibrated or swung about its pivot the greater will be the tension 70 of the spring against which said pole swings, and hence also the greater will be the pressure exerted upon the outer or contact end of such arm. It will also be observed that trolley-supports constructed in accordance 75 with my invention do not swing upon any particular center, as the center changes with the different positions to which the pole is swung in order to produce an equilibrium between the nine springs employed.

I do not desire to be limited or restricted to the exact details of construction shown and described, as many variations therefrom would readily suggest themselves to persons skilled in the art and still fall within the 85 spirit and scope of my invention; but,

Having now fully set forth the object and nature of my invention and a form of apparatus embodying the same, and having explained the construction, function, and mode 90 of operation thereof, what I claim as new and useful and of my own invention, and desire to secure by Letters Patent of the United States, is—

1. In a trolley-support for electric railways, 95 a trolley-pole, a series of springs arranged to support said pole, said springs connected at one end to a fixed support and at the other to said pole, the pole connection of certain 100 of said springs being movable with respect to the pole connection of others of said springs; as and for the purpose set forth.

2. In a trolley-support, a trolley-pole, a series of springs connected at one end to said pole, and a second series of springs having 105 sliding connection with said pole; as and for the purpose set forth.

3. In a trolley-support, a base, a series of 110 springs connected at one end to said base, a trolley-pole, certain of said springs being fixedly connected at their other ends to said pole, and the other of said springs having sliding 115 connections with said pole adapted to move lengthwise thereof, whereby said pole is supported by said springs and is permitted universal movement; as and for the purpose set forth.

4. In a trolley-support, a base, a series of 120 springs connected at one end thereof to said base, a trolley-pole having a sliding collar thereon, certain of said springs connected at the other end thereof rigidly to said pole, and the other of said springs being connected to 125 said collar; as and for the purpose set forth.

5. In a trolley-support, a base, a series of 130 pairs of springs connected at one end to said base, a trolley-pole, said springs connected at the other end to said pole, one member of each pair of said springs being slidably connected to said pole; as and for the purpose set forth.

6. In a trolley-support, a base, a trolley-pole, a fixed and a loose sleeve mounted on said pole, a series of springs connected at one end to said base, a portion of said springs be-

ing connected at the opposite end thereof to said fixed sleeve, and a portion to said sleeve; as and for the purpose set forth.

7. In a trolley-support, a base, a trolley-pole, and a loose sleeve mounted on said pole, a series of springs connected at one end to said base, a portion of said springs connected at the opposite end thereof to said fixed sleeve and a portion to said loose sleeve, and a spring interposed between said sleeves; as and for the purpose set forth.

8. In a trolley-support, a base having posts rising therefrom at suitably-spaced distances apart, a pair of springs connected at one end to each of said posts, a trolley-pole, one member of each of said pair of springs being fixedly connected to said pole and the other member of each of said pair of springs having a sliding connection with said pole; as and for the purpose set forth.

9. In a trolley-support, a base, a series of

springs, a trolley-pole, a fixed and a sliding sleeve mounted thereon, the members of said pairs of springs being connected at one end to said base and at the other end to said fixed and sliding sleeves respectively; as and for the purpose set forth. 25

10. In a trolley-support, a base, a series of pairs of springs, a trolley-pole, a fixed and a sliding sleeve mounted thereon, the members 30 of each pair of springs being connected at one end to said base, and at the other end to said fixed and sliding sleeve respectively, and a spring interposed between said sleeves; as and for the purpose set forth.

In witness whereof I have hereunto set my hand this 3d day of June, 1896.

SIDNEY H. SHORT.
